UNITED STATES PATENT OFFICE

164,940

SCARF

Vera Neumann, Ossining, N. Y.

Application February 1, 1951, Serial No. 14,071

Term of patent 7 years

(Cl. D3—12)

To all whom it may concern:

Be it known that I, Vera Neumann, a citizen of the United States, residing in Ossining, Westchester County, State of New York, have invented a new, original, and ornamental Design for a Scarf, of which the following is a specification, reference being had to the accompanying drawing, constituting a part hereof. The single figure of the drawing is a plan view of a scarf illustrating my new design. The reverse side is similar to the obverse.

I claim:

The ornamental design for a scarf, substantially as shown and described.

VERA NEUMANN.
